To all whom it may concern:

Be it known that I, JAMES MARSDEN, a subject of the Queen of Great Britain, residing in Wigan, in the county of Lancaster, England, have invented and produced a new and original Design for a Pattern-Chart, of which the following is a specification, reference being had to the accompanying drawing, forming a part thereof.

10 The drawing is a plan view of a pattern-chart, showing my new design.

As shown in the drawing, the leading or material feature of my design consists of a pattern-chart having represented thereon the 15 novel arrangement of patterns for boys' Norfolk jackets and trousers, as now described.

At one side of the pattern-chart is shown the jacket fore part C, having pocket position indicated at c and the position of buttons indicated by stars, the inside collar I, the pocket-facings J J, the top side sleeve F, the jacket fore part C, having pocket position indicated at c, the top side pieces of trousers, B B B, the trousers-fly V, the under side of trousers, 25 A, the under side of sleeves, M M, the jacket-

facing O, the front plaits P P, patch-pocket pieces S S, jacket-facings O O, and pocket-facings T T. At the other side of the pattern-chart is shown the jacket fore part C, having pocket position indicated at c, the back plaits 30 E E, the fore-part plait H, the back G, the top sleeve parts L L, the under sleeve part M, the jacket-back N, the under side of trousers, A, the trousers fly-pieces V V, outside-collar pieces Q Q Q, the jacket-facing O, the under 35 side of trousers, R, pocket-facing T, and the belts U U U.

Having thus described my invention, what I claim as new therein, and desire to secure by Design Letters Patent, is—

The design for a pattern-chart substantially as herein shown and described.

In witness whereof I have hereunto signed my name, this 5th day of September, 1898, in the presence of two subscribing witnesses. 45

JAMES MARSDEN.
